SPRING SEAT CONSTRUCTION

Hyland C. Flint, Detroit, Mich., assignor, by direct
and mesne assignments, to Patent Sales, Inc.,
a corporation of Michigan

Application June 24, 1935, Serial No. 28,181

7 Claims. (Cl. 155—53)

This invention relates to a seat construction and has special reference to a spring unit for use in chairs, davenport, vehicle seats or furniture or other constructions wherein it is desired 5 to provide a synchronization of the movable members thereof in order to effect a floating support for the user in which a minimum number of moving parts is utilized to effect the unison of movement.

10 More particularly, this invention relates to a spring unit construction for chairs, davenport, vehicle seats or the like preferably of the unison type wherein the back rest is synchronized in its vertical movement with the movement of the seat, 15 in which unit the back rest is provided with a primary flexible supporting means of relative stiffness, and a secondary flexible supporting means of relative softness for supporting the back of an occupant in a natural posture.

20 When one is seated in a chair or other article of furniture having a seat and a back rest that are provided with deep padding, springs or other shock absorbing material, and the seat thereby being capable of substantial vertical 25 movement and the back rest of substantial horizontal movement, there are two directions of movement made by the body, one being vertically with the seat frame, the other being horizontally against the back rest. The pivot point 30 at the hip, where the limbs of a person join the trunk, permits this double motion. Therefore, a chair or seat to be really comfortable should provide the above double motion in unison in the same manner that the body of a person performs 35 its movements in unison.

However, it has been found that the body of a person occupying a seat is susceptible of another motion at a portion located at the small of the back which in effect is likewise a pivotal 40 point. In other words, that part of the body above the small of the back may, and should lean farther back into the back rest than that portion substantially at the small of the back 45 in order that the back as a whole may maintain its natural posture without effort. The back should be supported in a concave position, and therein lies the secret of real relaxed comfort in any type of seat. Therefore, a seat should 50 incorporate the above features to permit such a posture with unison of movement of seat and back rest so that the firmness at the small of the back will at all times be in the proper position, regardless of how much or how little the 55 seat moves up or down by the varying weights

of persons using the seat, and the present invention contemplates such provision.

In the case of a seat in a moving vehicle, it would be desirable to provide a rather firm support for the kidneys and that portion of the body at the small of the back. But at present nearly all vehicles, and particularly motor cars, have what is called "pitch" or the tendency to throw the passenger away from the back of the seat. In order to prevent this "pitch" as far as possible, it has been necessary to make the vehicle back rest very soft and resilient. It can be seen that if the entire back rest of a seat were firm, the pitching would be accentuated. It can also be seen that all softness of the back rest allows the back of a person to fall into a convex or bow shape, unless physically resisted, due to the third point of pivot or joint at the small of the back. However, if that portion above the small of the back were very soft and that portion at the small of the back were much firmer, the seat would thereby provide an ideal back rest that would absorb to a large degree the pitching and yet provide a firm support at the small of the back, provided, however, that this 20 double type of support could move in accurate unison with the seat. If this unison of movement is not obtained, then the firm support intended for the small of the back would not be in a proper position and would not obtain the 30 desired advantages. It is urged, therefore, that a construction, wherein a relatively stiff flexible support is employed at the proper location in a back rest and allowed to move vertically with the seat, thereby maintaining the proper location, would prevent that tiresome feeling that a wholly soft back rest gives from too little positive support at the small of the back.

One of the objects of this invention is to provide a seat construction as above characterized, 40 in which the back rest thereof is capable of unison movement with the vertically movable seat, the back rest being capable of relative rigid and flexible support within itself, and the supporting means lying in a common plane.

Another object of this invention is to provide a seat construction as hereinabove noted, wherein at last one of the supporting means of the back rest shall furnish the means for unison of movement thereof with the seat.

A further object of this invention is to provide a seat construction, wherein at least two points of pivotal support are provided in order to maintain a natural posture of an occupant in a relaxed position.

Other objects and advantages will hereinafter be more particularly pointed out, and for a more complete understanding of the characteristic features of this invention reference may now be had to the following description when taken together with the accompanying drawings, in which latter:

Figure 1 is a perspective view of an unupholstered seat construction embodying the features of this invention showing the means for unison movement of the back rest and the seat, and also showing one of the relatively stiff supporting means of the back rest in full lines and the relatively soft flexible supporting means in dotted lines;

Fig. 2 is a front face view of the construction as shown in Fig. 1, a portion of the relatively soft flexible supporting lines being shown in section;

Fig. 3 is a side view of the construction of Fig. 2 with a portion of the back rest frame cut away;

Fig. 4 is a plan view of Fig. 2 with the soft flexible means removed;

Fig. 5 is a view similar to Fig. 3 showing a modified form of construction in which a definite pivot point is provided in the back rest frame substantially at the portion where the small of the back of an occupant contacts therewith;

Fig. 6 is a perspective view of the back rest frame of Fig. 5;

Fig. 7 is a vertical sectional view of a modified form of seat construction as embodied in an article of upholstered furniture;

Fig. 8 is a diagrammatic side elevational view of a conventional seat construction showing the normal position of an occupant therein and the definite independence from each other of the seat and back rest; and

Fig. 9 is a view similar to Fig. 8 of the present seat construction showing the normal position of an occupant therein.

Referring now to the drawings, and more particularly to Figs. 1 to 4, inclusive, thereof, the construction of this invention is shown in one form as comprising a base 10 which may be provided with any suitable legs or other means of support to space it from the floor when desired. In the present figures under consideration, the base 10 is shown as comprising a flat solid member, preferably of wood. It is, of course, to be understood that the base illustrated may be of any desired shape, construction, or materials without departing from the spirit of this invention, since any type of base may be employed that is suitable for supporting a resilient seat construction.

A plurality of spaced compression springs 14 are mounted on the base 10 in any desired manner, the compression springs 14 supporting a seat frame 15. The seat frame preferably comprises a substantially rectangular member of which the sides and front are of wood to facilitate the fixing of the upholstery thereto and of which the back is a wire rod 16 forming a hinge for pivotal connection with the back rest 17. It is understood that the seat frame need not necessarily be partially of wood since the rod 16 may extend to form a supporting edge for the upholstery. The two side members of the frame 15 are shown as substantially higher than the front member in order to provide a pocket-like portion in which the usual padding of cotton or hair may be placed. Also, a definite contour similar to the contour of the back rest is thus provided so as to maintain the outside contour of the whole seat pleasing in

design, without detracting from the comfort and resiliency of the seat as a whole.

The shape and construction of the seat frame, of course, may be varied with the usual practices, since the present showing of the seat frame is merely for illustrative purposes. The seat frame, therefore, is capable of vertical movement against the compression of the springs 14. A pair of spaced vertically extending supports 19 are fixed to the base 10 against movement and comprise preferably heavy rigid channel members, preferably of steel. The vertically extending supports 19 are encased in the back rest frame 17, preferably formed of sides 20 and back 21 of wood or sheet metal of any design. Adjacent each side of the frame is disposed a housing 22 formed preferably of a strip of sheet metal of L-shape having one end secured to the back 21 and the other end to one of the sides 20 in such a manner as to surround and enclose the upper part of the supports 19. These separate housings 22 act as means to attach the vertical actuating mechanism to the floating back rest in resilient connection with the fixed supports 19. Interposed between the upper ends of each of the supports 19 and the front face 25 of the housing 22 is a comparatively stiff compression spring 24, one end of each of the compression springs being fixed to a rocker 25 pivotally connected to the supports 19, and the other end of each of the compression springs being fixed to a rocker 26 connected to, and for pivotal movement with, the housing 22. A flat hinge-like member 24a is connected in the manner of the spring 24 to prevent sidewise movement of the box-like back rest 17.

The members 25 and 26 are free to partake of a limited rocking movement without allowing the compression springs or coils 24 to buckle or the convolutions thereof to become displaced to any substantial degree from their common axes when movement is had of the frame 21 in a vertical direction. Such a construction, showing the use of rockers for the use of the support of coils, is shown and described in a patent issued to the inventor hereof on December 26, 1933, Patent No. 1,940,853. However, the coil springs mounting of the patent is shown herein for illustrative purposes only, and it is understood that the present invention is not to be limited to that particular type of support.

The comparatively stiff compression springs 24 will hereinafter be called the "primary" flexible supporting means of the back rest. Their function is two-fold; first to tend to resist the horizontal movement of the back rest and the person leaning thereon, and second, to connect the back rest with the vertically extending supports 19. The springs should be capable of only slight compression, or in other words, offer substantial resistance, and therefore provide a firm feeling which is transmitted to substantially the small of the back by reason of the spacing thereof.

Referring now to Figs. 2 and 3, there will be seen interposed between and above the primary springs and the housing 22 a pad of soft resilient springs 28, hereinafter called the "secondary" flexible supporting means of the back rest. In this instance of use, there is illustrated preferably what is known as Marshall springs in a unit pad comprising soft springs, each of which is enclosed in a muslin bag. It is to be understood, of course, that any kind of secondary flexible supporting means may be used, such as hair, 75

hair dipped in gummed rubber, cotton or other soft resilient material, the Marshall springs being used for illustrative purposes only.

Although the primary flexible supporting means is located substantially at the small of the back of the person leaning against the back rest, it has been found that the relatively stiff flexibility thereof, as distinguished from the relative softness of the secondary flexible supporting means, should not be too apparent but should, in effect, impart a firmness to the whole floating frame of the back rest and at the same time impart an indirect yet firm support to the small of the back of the person only on each side of that portion of the body. In between the primary supporting means, the secondary means should reach down to the bottom of the back rest in order that the spine may have a soft place against which to rest, but the natural curve of the back will still be supported firmly by the primary means on each side of the spine.

Referring now more particularly to Figs. 8 and 9, a natural and an unnatural sitting posture are illustrated. In Fig. 8 the occupant has no firm support for that portion of the small of his back from which he bends forwardly or rearwardly. The compression springs of the back rest in this figure are capable only of effecting a uniform resistance throughout, and the portion of the back exerting the greatest pressure will be permitted to travel the greatest distance, thereby effecting an unnatural curved or bowed posture. Further, the relative movement between the seat and the back rest promotes a creeping of the clothes of the wearer. However, in Fig. 9, the compression springs are not uniform but, on the contrary, offer the greatest resistance over that portion of the back where the greatest pressure is obtained to offer a comparatively firm yet flexible support thereat. The posture resulting from such a support is illustrated in Fig. 9 and is uniformly correct for all normal occupants. This support is afforded continuously, irrespective of whether the seat is compressed by an occupant or extended to its normal position. No creeping of the clothes need occur.

It may be found desirable, under some circumstances, to permit more backward movement of the body of a person above the small of the back than the forms in Figs. 1, 2, and 3 would allow. In these forms the effect of softness above the primary means would be limited to the extent that the fullness of the upholstery cover could flex backward and forward between the hard edges of the sides of the frame 21.

Referring to Figs. 5 and 6, there is shown a modification of the back rest frame 21 of Figs. 1, 2, and 3, the elements of the latter figures being the same with the exception of the sides 20 which are cut away at 21^a above the primary supporting means and above the small of the back of a person. A wire member 28 is pivoted at 30 within the cut-away portion to act as an edge support for the upholstery. The secondary supporting means 28^a can be, if desired, fastened to this border wire, and it will be clear, therefore, that a much greater backward movement will be allowed without tearing or wearing of the upholstery cover which latter may be made up in a continuous strip.

In the operation of the above seat constructions the seat frame 15 is moved downwardly in a substantially vertical direction by the weight of an occupant, the seat being prevented from horizontal movement by a guide rod 31 disposed

on each side thereof and connected at one end thereof to an upright 32 as by means of a rivet and at the other end thereof to the rear end of the seat. The rod 16 of the seat 15, being pivotally connected to the lower end of the back rest 17, carries the forward edge thereof downwardly with the seat to provide a unison of vertical movement.

The back of an occupant may rest against the upholstery of the back rest 17 and the box-like frame surrounding the upright supports 19 moves rearwardly as a unit against the resistance of the primary flexible supporting means, the contour of the back being fitted in restful supporting comfort by the secondary flexible supporting means.

There is a definite co-operation between the specific type of flexible supporting means in the back rest and the unison seat. If the back rest did not move vertically in unison with the seat, the primary and secondary types of flexible supporting means would lose their more desirable effectiveness. The primary flexible supporting means should follow the movement of the back of the individual to offer support continuously over the desired portion thereof, the same being true of the secondary flexible supporting means.

Referring now particularly to Fig. 7 of the drawings, the seat construction is shown as being embodied in an article of furniture. In this case a pair of guide rods 31^a are disposed on opposite sides of the seat, each rod being pivotally attached at one end thereof to an upstanding rigid support 32^a secured to the base 18^a. The other end of the guide rod 31^a is pivotally secured as at 31^b to the lower forward end of a floating frame indicated as a whole by the numeral 21^a. The function of the guide rod 31^a is to force the floating frame 21^a to move in a fixed substantially vertical path, the lower end of the frame having only such relative horizontal movement as is necessitated by the radius of the guide rod 31^a.

In the previously described embodiment, the wooden frame 15, shown particularly in Fig. 1, is supplanted in the present instance by a substantially rectangular wire frame 15^a, each of the rear ends of which is attached to the pivotal connection 31^b between the guide rod 31^a and the lower end of the floating frame 21^a. The front free end of the wire frame 15^a is movable vertically against the resistance of the coil springs 14^a on which the frame rests. The primary purpose of the wire frame is to retain the upholstered seat in a desired shape. In this manner the whole front of the seat is soft and flexible and presents no hard front edge to the occupant.

The floating frame 21^a comprises preferably a sheet metal member 28^a extending across the rear of the back rest having a preferably sheet metal channel strip 22^a on each side thereof in alignment with rigid supports 19^a extending upwardly from and fixedly secured to the base 18^a, each of the strips 22^a having a substantially U-shaped intermediate portion upon which a rocker 26^a is pivotally mounted. A similar rocker 26^a is pivotally mounted on the upper end of the rigid support 19^a for co-operation with the pivotally mounted rocker 26^a to receive a primary spring 24^a in the same manner as described with reference to the preceding modifications. The floating frame 21^a is therefore movable in a horizontal direction against the resistance of the primary springs 24^a.

The back rest is also provided with a substan-

tially rectangular wire or other flexible frame 17^a for the purpose of retaining the upholstery in a desired shape and for the further purpose of permitting the secondary springs 28^a to flex 5 in any desired manner. The secondary springs are disposed between the sheet metal back 26^a and the wire frame 17^a to be enclosed by the upholstery and to permit horizontal movement of the body of the occupant against the resistance 10 of the springs. The wire frame 17^a is not connected to any fixed support but is merely held between the secondary springs 28^a and the upholstery. The frame 17^a, while having independent horizontal movement, is required to follow accurately the vertical movement of the seat 15 since the forward end of the bottom of the back rest overlies and is supported by the rear end of the seat.

In the operation of the structure just described, the weight of a person on the seat will compress the springs 14^a and permit the frame 15^a to drop downwardly. The back rest is supported by the seat frame 15^a and will therefore move downwardly therewith. The back rest when engaged by the weight of a person resting thereagainst will move as a whole rearwardly horizontally against the compression of the coil spring 24^a and the curvature of the body of a person will be accommodated by the relatively soft coil springs 30 28^a.

While several embodiments are herein shown and described, it is to be understood that various modifications thereof may be apparent to those skilled in the art without departing from the spirit and scope of this invention, and, therefore, the same is only to be limited by the scope of the prior art and the appended claims.

I claim:

1. In a device of the character described, a base 40 for resting on a supporting surface, a horizontally extending seat frame, movable means on said base supporting said seat frame for vertical movement thereof, a substantially vertically extending support fixed relative to said base, a substantially 45 vertically extending back rest comprising a single housing of box-like formation enclosing said fixed support and engaging said seat frame for vertical movement therewith and having horizontal movement relative thereto, and relatively stiff 50 and other relatively soft flexible supporting means confined within said housing to follow the vertical movement thereof, said relatively soft flexible supporting means being supported by said housing, and means connecting said stiff flexible 55 supporting means to said fixed support and to said housing for permitting free floating movement of said housing, said stiff flexible supporting means being adapted to offer relatively great resistance to the movement of said housing as a 60 whole and said soft flexible supporting means being adapted to offer relatively little resistance within said housing to the horizontal movement of the body of an occupant resting thereagainst.

2. In a device of the character described, a base 65 for resting on a supporting surface, a horizontally extending seat frame, movable means on said base supporting said seat frame for vertical movement thereof, a substantially vertically extending support fixed relative to said base, a substantially 70 vertically extending back rest comprising a single housing of box-like formation enclosing said fixed support and engaging said seat frame for vertical movement therewith and having horizontal movement relative thereto, and relatively stiff and other relatively soft flexible 75

supporting means confined within said housing to follow the vertical movement thereof, said relatively soft flexible supporting means being supported by said housing, and means pivotally connecting said stiff flexible supporting means to said fixed support and to said housing for permitting free floating movement of said housing, said stiff flexible supporting means being adapted to offer relatively great resistance to the movement of said housing as a whole and said soft flexible supporting means being adapted to offer relatively little resistance within said housing to the horizontal movement of the body of an occupant resting thereagainst.

3. In a device of the character described, a base for resting on a supporting surface, a horizontally extending seat frame, movable means on said base supporting said seat frame for vertical movement thereof, a substantially vertically extending support fixed relative to said base, a substantially 20 vertically extending back rest comprising a single housing of box-like formation enclosing said fixed support and engaging said seat frame for vertical movement therewith and having horizontal movement relative thereto, and relatively stiff compression springs and relatively soft flexible supporting means confined within said housing to follow the vertical movement thereof, said relatively soft flexible supporting means being supported by said housing, and means pivotally connecting said stiff compression springs to said fixed support and to said housing for permitting free floating movement of said housing, said stiff flexible compression springs being adapted to offer relatively great resistance 30 to the movement of said housing as a whole and said soft flexible supporting means being adapted to offer relatively little resistance within said housing to the horizontal movement of the body of an occupant resting thereagainst.

4. In a device of the character described, a base for resting on a supporting surface, a horizontally extending seat frame, movable means on said base supporting said seat frame for vertical movement thereof, a substantially vertically extending support fixed relative to said base, a substantially vertically extending back rest comprising a single housing of box-like formation enclosing said fixed support and engaging said seat frame for vertical movement therewith and having horizontal movement relative thereto, and relatively stiff and other relatively soft sets of compression springs confined within said housing to follow the vertical movement thereof, said relatively soft compression springs being supported by said housing, and means pivotally connecting said stiff flexible set of compression springs to said fixed support and to said housing for permitting free floating movement of said housing, said stiff flexible set of compression springs being adapted to offer relatively great resistance to the movement of said housing as a whole and said soft flexible set of compression springs being adapted to offer relatively little resistance within said housing to the horizontal movement of the body of an occupant resting thereagainst.

5. In a device of the character described, a base for resting on a supporting surface, a horizontally extending seat frame, movable means on said base supporting said seat frame for vertical movement thereof, a substantially vertically extending support fixed relative to said base, a substantially vertically extending back rest comprising a single housing of box-like formation 70

- enclosing said fixed support and engaging said seat frame for vertical movement therewith and having horizontal movement relative thereto, and relatively stiff and other relatively soft flexible
- 5 supporting means confined within said housing to follow the vertical movement thereof, said relatively soft flexible supporting means being supported by said housing, and means connecting said stiff flexible supporting means to said fixed
- 10 support and to said housing for permitting free floating movement of said housing, said stiff flexible supporting means being adapted to offer relatively great resistance to the movement of said housing as a whole and said soft flexible
- 15 supporting means being adapted to offer relatively little resistance within said housing to the horizontal movement of the body of an occupant resting thereagainst, said housing including portions enclosing said vertically extending fixed
- 20 support and projecting rearwardly thereof whereby said seat frame and housing are adapted to be upholstered by a preformed continuous strip entirely enclosing the same.
6. In a device of the character described, a
- 25 base for resting on a supporting surface, a horizontally extending seat frame, movable means on said base supporting said seat frame for vertical movement thereof, a substantially vertically extending support fixed relative to said base, a
- 30 substantially vertically extending back rest comprising a rear comparatively rigid base having forwardly extending rigid arms and a flexible frame spaced from said rigid base, said rigid base pivotally engaging said seat frame for vertical
- 35 movement therewith, and relatively stiff and other relatively soft flexible supporting means lying adjacent said forwardly extending rigid arms to follow the vertical movement thereof, said relatively soft flexible supporting means engaging said
- 40 rigid base and resiliently supporting said flexible
- frame of said back rest, and means connecting said stiff flexible supporting means to said fixed support and to said rigid arms for permitting free floating movement of said housing, said stiff flexible supporting means being adapted to offer relatively great resistance to the movement of said housing as a whole and said soft flexible supporting means being adapted to offer relatively little resistance within said housing to the horizontal movement of the body of an occupant resting thereagainst.
7. In a device of the character described, a base for resting on a supporting surface, a horizontally extending seat frame, movable means on said base supporting said seat frame for vertical movement thereof, a substantially vertically extending support fixed relative to said base, a substantially vertically extending back rest comprising a rear comparatively rigid base having forwardly extending rigid arms and a wire frame spaced from said rigid base, said rigid base pivotally engaging said seat frame for vertical movement therewith, and relatively stiff compression springs and relatively soft flexible supporting means lying adjacent said forwardly extending rigid arms to follow the vertical movement thereof, said relatively soft flexible supporting means engaging said rigid base and resiliently supporting said wire frame, and means pivotally connecting said stiff flexible compression springs to said fixed support and to said rigid arms for permitting free floating movement of said housing, said stiff flexible supporting means being adapted to offer relatively great resistance to the movement of said housing as a whole and said soft flexible supporting means being adapted to offer relatively little resistance within said housing to the horizontal movement of the body of an occupant resting thereagainst.

HYLAND C. FLINT. 40
